US00D776804S

(12) **United States Design Patent** (10) **Patent No.:** **US D776,804 S**
Meyer (45) **Date of Patent:** **** Jan. 17, 2017**

(54) **OSCILLATING POSITIVE EXPIRATORY
PRESSURE DEVICE**

2,918,917 A 12/1959 Emerson
3,710,780 A 1/1973 Milch
3,908,987 A 9/1975 Boehringer
4,054,134 A 10/1977 Kritzer
4,062,358 A 12/1977 Kritzer
4,182,366 A 1/1980 Boehringer

(71) Applicant: **Trudell Medical International**, London (CA)

USPC **D24/110**

(57) **CLAIM**

(58) **Field of Classification Search**

The ornamental design for an oscillating positive expiratory pressure device, as shown and described.

USPC D24/107–108, 110–114, 127, 162, 164,
D24/185–186
CPC A61M 15/0065; A61M 11/005; A61M
15/0091; A61M 15/0085; A61M 11/00;
A61M 15/00; A61M 11/04; A61M 16/00

DESCRIPTION

See application file for complete search history.

FIG. 1 is a perspective view of an oscillating positive expiratory pressure device showing the new design;

(56) **References Cited**

FIG. 2 is a rear view thereof;

U.S. PATENT DOCUMENTS

FIG. 3 is a front view thereof;

393,869 A 12/1888 Warren
938,808 A 11/1909 Yount
2,670,739 A 3/1954 McNeill

FIG. 4 is a top view thereof;

FIG. 5 is a bottom view thereof;

FIG. 6 is a left-side view thereof; and,

FIG. 7 is a right-side view thereof.

The broken lines in the drawings illustrate portions of the oscillating positive expiratory pressure device that form no part of the claimed design.
